Isaac W. Elmore of Lyons New York
Sellers Patent

This is to refer to as three letters Patented making part of the same
containing a description in the words of the said Isaac W. Elmore himself of
his improvement in dressing Mill Stones.

To all whom these presents shall come, Be it known that Isaac
W. Elmore of the town of Lyons in the County of Wayne and State of New
York, have invented a new and useful improvement in the dress of mill
stones, for the manufacture of flour and for grinding any substance or sub-
stances usually ground in mills, and that the following is a full and exact
description of said improvement as invented by me.

My improvement consists 1st In giving to the furrow of Mill Stones
a greater degree of angle or draught at and near the edge of the stones
in proportion to the degrees of angle or draught near the eye or centre
than has heretofore been used. 2nd In giving to the furrow at and near
the edge a greater degree of angle or draught than has heretofore
been used to give to furrow of Mill Stones in which the degrees of angle
or draught were equal in the furrow. The angle or degrees of angle or
draught which I claim as part of my improvement or invention may
be determined in the following manner, to wit. By using the segments
of circles of any diameter from two to that of three feet and also the seg-
ments of circles of six or any intermediate diameter, between those of two
and of three feet, on a stone the diameter of which is six feet (and in that
proportion for stones of any other diameter) as follows. Place one of the
points of an instrument proper for describing or describing circles at or as
near the centre of the stone as you choose (or in other words commencing
with or without draught at the eye) using the other point as a pivot,
and except or describe the segment of a circle from thence to the edge, the
radius or sweep used must be in proportion to the diameter of the stone to
which it is applied in the ratio above claimed. After I have used the circle
and segments of circles to convey a knowledge of the principle of my improvement
yet I do not consider myself bound or confined to the use of them to obtain the

required draught of the furrow. Therefore any other form or shape of furrow than those produced by the use of the circle, or segments thereof having the relative amount of draught, or degrees of angle. I also claim as part of my improvement the degrees, or amount of draught produced by the segment of a circle whose diameter is, four feet is the least or smallest; and the segments of a circle whose diameter is, three feet will produce the greatest amount or ratio of draught when applied to a stone of four feet in diameter in the manner before described, and the same ratio or relative amount of draught is claimed for mill stones, of all or any other diameter as my improvement.

Some of the objects to be attained by the use of my improvement in draft, will be better understood by stating some of the difficulties attending on the former modes of draft now in use. 1st The quarter draft, which is, the one now in general use, is one in which the furrows have an unequal draught, to wit some furrows have more draught than others, consequently the grinding cannot be performed in an even and uniform manner. For if those furrows, which have the greatest draught do not force the meal out from under the stone until the process of grinding is finished, it is evident that those furrows of less draught will not force it out until a portion of the meal or flour is injured. Another objection is, that there is, too great a draught given to the furrow, &c and near the eye of the stone in proportion to the draught at and over the ridge, thereby forcing the grain while in a coarse state towards the regeneration, it is necessary to use more weight consequently requiring more power to perform the operation, than would be necessary if a greater share of the work was performed near the eye, and also generating a greater deposit of heat than is proper for the benefit of flour. 2nd Those modes of draft, now in use, in which the furrows have an equal draught, grind too slow, because the furrows have so little draught on the ridge of the stone that they cannot discharge the meal as soon as it is sufficiently ground in consequence of which the edges of the furrows and other cutting parts of the stone are continually encumbered with flour or meal which ought to be discharged, thereby preventing the stone from cutting free and clear by reason of which the grain is reduced to flour more by pressure and less by cutting than it should be, (this will also apply to the quarter draft, according to cleanness and heavy, in)

which state it will not bolt free, neither will rise so well in baking.
My improvement is intended to obviate these difficulties. 1° By equalizing
the draught in all the furrows, it obviates the difficulty which for want of
that equality is inseparable from the use of the quarter stones.

2° By giving to the furrows a less proportion of draught near the eye,
the stones are enabled to perform a greater portion of grinding in that region
where less power is required to perform the work, than near the verge.

3° By constantly increasing the draught on the furrows as they approach
the eye in a greater ratio than has heretofore been used, thereby enabling
them to overcome the increasing difficulty of forcing the meal onward as it
increases in fineness (which the accelerated motion of the verge of the stones
with the modes of draft heretofore used is not sufficient to perform)
thereby discharging the meal as soon as it is sufficiently ground leaving the
furrows, and other cutting parts, of the stone unencumbered by reason of
which the grinding will be done with less pressure and less force, and con-
sequently less heat will be generated in the operation, the meal being cooler
and more even will bolt more freely and the flour will be less liable to sour.
This improvement is calculated to take the best possible advantage of the
power to be applied to all sizes, and velocities of stones, to wit, the seven feet
circle commencing the furrows, it or near the centre, is best for stone that runs
with considerable velocity, not having sufficient power to bear a heavy
load. And as the draught of the furrows are increased by lessening the
circle, so the feed must be increased, and an additional power will be requi-
red. It is believed from the experiments already made that a five feet
stone having the furrows, one circle of five feet commencing two or three inch-
es from the centre, is capable of doing the greatest amount of grinding (it must
be observed however that the experiments were made on the wheat ground in
the western part of this State, which wheat is more tender than that in the
Eastern part, and much more so than that in the Southern States. It will
be necessary therefore to make an appropriate allowance according to the quality
of the wheat to be ground, to wit, the harder the wheat is to grind, the longer
it will require to be under the stones, consequently a less draught in the fur-
rows will be necessary.) Experiments have been made on nearly all the large

to six inches less than the size of the stone; this last the furrow, one full in from the centre and it is found to require less power for the operation of grinding in proportion as the draught is less at the eye; it also requires a slower motion than that in a larger circle. The smallest circle gives the greatest draught on the edge of the stone, and the intention is, to make the draught of the furrow, at and on the region of the eye small as may be thereby enabling the stone to perform all the grinding possible in that quarter, and the draught being great in the edge is calculated to make less in that region and near the edge of the stone, the less power it will require to perform the operation and is calculated for a slow motion. It will therefore be applied differently where there is a want of power. The number of furrows necessary for stone, must in some measure depend on their qualities, say for a few feet from thirty four to forty as the case may require, from one to one and a quarter ^{or two inches} running every other one into the eye (those may be diminished leading furrow, those between running to a point near the eye, being careful not to run up so far as to cut up the face of the stone too much) leaving the lands at the point between the leading furrow, nearly as wide as those on the edge. But this ought also to depend some on the quality of the eye blocks. In laying out the furrow, get out the furrow sticks of the dimensions wanted in such a manner as to fasten it at the centre of the stone so as to turn it round. The stone being divided off on the edge for the required number of furrow, proceed to lay out every other one running them into the eye. Then lay out the others only running them up from the edge say one third of the way to the eye, then place the front edge of the furrow stick where you left off on the back line, draw a line from thence in toward the eye. The back part of the furrow will be finished, then place the back edge on the front line etc. this will bring the furrow to a point, as to the depth of every furrow, care should be had that the depth and width should be in proportion so that the rise from the bottom and back part of the furrow be gradual and easy of ascent, care should also be had that the stones have a good face all the way to the eye. In fastening where I have hereunto set my hand
